DAM

Jacques Mesnager, Paris, France

Application June 29, 1948, Serial No. 35,754
In France July 2, 1947

6 Claims. (Cl. 61—30)

1

The present invention has for its object a constructional method of building dams, sluice-gates, walls of reservoirs or channels containing liquids which is characterised thereby that the water-retaining dam facing is constituted by a flexible wall free to yield to the pressure of the liquid so as to assume a self-balance.

The pressure or thrust of the water subjects a deformable wall in the vertical plane to either tensional or compressive stresses depending on whether the curved vertical outline of the wall is intended to resist the hydrostatic pressure with its concave or its convex side, at the same time as the anchorings by which it is secured at its edges are similarly subjected to either tensional or compressive stresses.

The deformable wall assumes the shape of a catenary curve which is the resultant of the pressures or thrusts of the liquid and of its own weight; this shape is an elastic plane or linear Bernouilli's curve, where the weight of the wall is negligible. This curve varies with the level of the liquid ahead of the dam.

The flexible wall is stressed tensionally in the vertical plane and free from any bending stress irrespective of the level of the liquid. It may therefore be constituted by a very thin membrane: a metallic sheet, asphalt- or tar-lined (contingently metal) cloth, waterproof cloth, etc.

Generally, only the atmospheric air is present on the opposite side of the water-retaining wall. According to a further feature of the invention, this atmospheric air may be replaced by pressure air, or gas, or liquid, which thus becomes effective to support the wall. This is possible where the deformable wall forms a sort of air or water chamber on whose wall the fluid compressed inside of it exerts a pressure that will support the wall. This arrangement allows to install adjustable dams or sluice-gates the height of which is variable in dependency on the pressure of the fluid and on the head.

Depending on whether a compressed fluid is used or not, and on whether the wall is stressed tensionally or compressively, different ways of carrying the invention into effect are possible, of which some are shown by way of example in the accompanying drawings.

Fig. 1 is a diagrammatic vertical sectional view of an embodiment comprising a deformable wall;

Figs. 2 and 3 are corresponding views of two modifications of the embodiment shown in Fig. 1;

Figs. 4 and 5 show two embodiments of a deformable wall whose upper edge can be wheeled on a rail displaced by means of a float;

2

Figs. 6 and 7 are diagrammatic vertical sectional views of two embodiments in which the deformable wall is stressed compressively;

Fig. 8 is a diagrammatic vertical sectional view of a deformable wall forming a chamber for pressure fluid;

Figs. 9 to 13 show various embodiments of a ribbed, a rippled or a flanged deformable wall;

Figs. 14 and 15 are views of two embodiments in which the liquid-retaining wall is rigid;

Fig. 16 is a view of an embodiment in which the wall can be wound up about a roller; and

Fig. 17 shows one further embodiment of a dam constructed in accordance with the present invention.

In the case of the Figure 1, an edge E of the deformable wall P is anchored in the soil S while the other edge F is propped by a support A which may be movable, for instance by the hinging of its two ends or the wheeling of its bottom end. This latter type of construction is shown in Fig. 17 where the support A in the form of rigid, planar frame, is connected to edge F of deformable wall P and fixedly connected at A to a platform Z mounted on rollers.

Means may be provided which allow lowering or raising the edge F so as to discharge the liquid retained over the same.

A considerable advantage of the constructional process according to the invention resides in the fact that the weight G of a huge mass of liquid retained contributes in ensuring the stability of the support A of the wall P. Effectively, in order to prevent the prop A from overturning, it is necessary that the resultant H of the pressure or thrust I and the weight G should go through the foot of the prop A. With this end in view, the weight G should not be too small as compared to the pressure or thrust I. Since the wall P according to the invention provides a curved facing, the weight of the liquid retained between the vertical planes of the edges E and F is large enough to ensure the stability of the support A and of the wall P, whereas in dams with a vertical or slightly sloping lining, it is necessary to use a huge mass of costly material to ensure this stability. The invention therefore cuts down the volume of materials to be used and consequently the costs of erection.

The support A may take different shapes some of which are as follows:

(a) A vertical (Fig. 1) or sloping (Fig. 2) propping wall which may be plane or cylindrical depending on whether the dam is straight or arcuate;

(b) Straight or curved vertical or sloping arcades (Fig. 3); and
(c) Posts.

The top edge of the wall P may be held by a movable support, for instance a pulley running on a rail and supporting the wall (Fig. 4), a support A running on the pulley, or a float u (Fig. 5) supporting the wall by buoyancy. In these embodiments, the support is only subjected to vertical stresses whilst the horizontal stresses are resisted by the anchorage of the wall P in the ground. A chain D prevents the float u from losing its trim.

The movability of the prop is advantageous in that it enables the movable wall to retain its catenary shape irrespective of the water level ahead of it.

As is shown in Fig. 16, the deformable wall P may be stressed compressively and show a convex shape on the side of the liquid retained.

With the bottom edge of the wall shored to the ground the top part may be held by the weight of the masonry, or by the stays L connected to a horizontal thin wall (Fig. 6) or anchored in the earth (Fig. 7).

The deformable wall P which on the one hand undergoes like in the previous cases tensile or compressive stresses in the vertical plane may on the other hand be subjected to stresses which may be null, or of tensile, or of compressive character depending on whether the dam is straight or has its concavity turned downstreams or upstreams.

In the embodiment of Fig. 8, the deformable wall P is subjected on its one side to the pressure of the liquid, and on the other to the variable pressure of a liquid Z compressed as desired. The two edges of the wall are anchored in the ground or in a mass integral therewith and the wall P forms a chamber into which a compressed fluid is forced by suitable means. Pipes X and Y are provided through which fluid can be forced in or let out. According to the pressure given to this fluid and according to the level of the liquid, the wall will take a defined shape. If the pressure of the compressed fluid decreases, the wall will collapse (position shown by the dotted lines) and the liquid retained can discharge over its top. Visible in Figure 8 are an inspection passage V and a pile-plank curtain or parapet wall W.

The wall P may be stiffened by horizontal ribs M (Fig. 9) even where it is deformable or according to lines of swiftest descent N (Fig. 10) where it is indeformable. In this case it may be composed of toric members T which may be stressed compressively (Fig. 11) or compressively (Fig. 12) in the horizontal direction.

The deformable wall consists of juxtaposed cylindrical sections B (Fig. 13) interconnected by cables or tie rods C or by stops the whole structure being braced.

There may be used, especially where the liquid level varies little, walls suitable stiffened so as to keep their shape irrespective of the liquid level, said shape may here again be a catenary corresponding to the pressures of the average level or to the one most frequently assumed by the liquid, or to the one which will give the lowest bending stresses when variation of the level is most unfavorable.

The wall may then be rested on props (Figs. 12 and 14) or on arcatures (Fig. 3), or braced (Figs. 6, 7, 13 and 14) or rested on spandrels by which it will be maintained not only at its top

edge but also at points intermediate between its top and its bottom edges.

Where the wall is thus stiffened, concrete (which may or may not be reinforced or pre-stressed) may advantageously be used as the building material.

Fig. 16 shows a further embodiment in which the flexible wall p is wound around a roller in the one direction while ropes Q retained at their top ends are wound on the roller R in the reverse direction. The pressure of the liquid retained by the wall tends e. g. to unwind the latter in the direction shown by the arrow in Figure 16 while the pull exerted on the ropes Q tends to rotate the roller R in the opposite direction. A balance will thus set in where the roller R and the one on which the flexible wall is wound are equal in diameter. The wall p is thus retained at its top edge. The weight of the rollers must be supported by suitable ropes or cables by means of which the system can be wound in or out as desired. The rollers for the winding of the flexible wall and of the ropes or cables may also be unequal in diameter. Racks may be substituted for the cables.

The ends of the roller R are received in grooves J provided in the walls O and can bear on the walls of said grooves.

What I claim as my invention and desire to secure by Letters Patent is:

1. A dam, comprising, in combination, a wall made of flexible sheet material and having substantially straight, parallel, and horizontal top and bottom edges extending across a body of water in which the dam is located with said bottom edge of said wall fixed to the bed on which the water is located, and said wall forming part of a cylinder having a horizontal generatrix substantially parallel to said top and bottom edges of said wall; and support means connected to said top edge of said wall to support said top edge for movement while maintaining said top edge parallel to said cylinder generatrix.

2. A dam, comprising, in combination, a wall made of flexible sheet material and having substantially straight, parallel, and horizontal top and bottom edges extending across a body of water in which the dam is located with said bottom edge of said wall fixed to the bed on which the water is located, and said wall forming part of a cylinder having a horizontal generatrix substantially parallel to said top and bottom edges of said wall; and support means connected to said top edge of said wall to support said top edge for free movement under the action of the body of water while maintaining said top edge parallel to said cylinder generatrix.

3. A dam, comprising, in combination, a wall made of flexible sheet material and having substantially straight, parallel, and horizontal top and bottom edges extending across a body of water in which the dam is located with said bottom edge of said wall fixed to the bed on which the water is located, and said wall forming part of a cylinder having a horizontal generatrix substantially parallel to said top and bottom edges of said wall; an upwardly extending support located adjacent said wall; a stationary rail mounted on said support, having an arm located over said top edge of said wall and extending in the direction transverse thereto; and a roller mounted on said arm for free movement therealong and being connected to said top edge of said wall.

70 4. A dam, comprising, in combination, a wall

75

made of flexible sheet material and having substantially straight, parallel, and horizontal top and bottom edges extending across a body of water in which the dam is located with said bottom edge of said wall fixed to the bed on which the water is located, and said wall forming part of a cylinder having a horizontal generatrix substantially parallel to said top and bottom edges of said wall; a float floating on the body of water and being connected to said top edge 10 of said wall to support the same for free movement under the action of the body of water.

5. A dam, comprising, in combination, a wall made of flexible sheet material and having substantially straight, parallel, and horizontal top and bottom edges extending across a body of water in which the dam is located with said bottom edge of said wall fixed to the bed on which the water is located, and said wall forming part of a cylinder having a horizontal generatrix substantially parallel to said top and bottom edges of said wall; and a planar supporting structure extending across and being movably mounted on the bed on which the body of water is located and having an upper edge portion 25 connected to said top edge of said wall to sup-

port the latter for free movement under the action of the body of water.

6. A dam as defined in claim 3 and wherein said upwardly extending support is in the form of a stationary elongated member extending upwardly from the bed on which the water is located.
